US0D1012702S

(12) **United States Design Patent** (10) Patent No.: **US D1,012,702 S**
(45) Date of Patent: ** Jan. 30, 2024

(54) **CONTAINER CAP**

(71) Applicant: **GIFLOR S.R.L.**, Grumolo Delle
Abbadesse (IT)

(72) Inventors: **Mattia Fracasso**, Vicenza (IT); **Paolo
Lobba**, Vicenza (IT)

(73) Assignee: **GIFLOR S.R.L.**, Vicenza (IT)

(**) Term: **15 Years**

(21) Appl. No.: **35/515,753**

(22) Filed: **Oct. 20, 2022**

(80) **Hague Agreement Data**

Int. Filing Date: **Oct. 20, 2022**

Int. Reg. No.: **DM/225171**

Int. Reg. Date: **Oct. 20, 2022**

Int. Reg. Pub. Date: **Dec. 9, 2022**

(30) **Foreign Application Priority Data**

Apr. 26, 2022 (EM) 009003924-0001

Apr. 26, 2022 (EM) 009003924-0002

& Birch, LLP

(57) **CLAIM**

The ornamental design for a container cap, as shown and
described.

DESCRIPTION

1. Container cap
3. Container cap
5. Container cap
7. Container cap
9. Container cap
11. Container cap
13. Container cap
15. Container cap

1.1 : Perspective view in a closed configuration

1.2 : Perspective thereof

1.3 : Front thereof

1.4 : Back thereof

1.5 : Left thereof

1.6 : Right thereof

1.7 : Top thereof

1.8 : Perspective view in a open configuration

3.1 : Perspective view in a closed configuration

3.2 : Perspective thereof

3.3 : Front thereof

3.4 : Back thereof

3.5 : Left thereof

3.6 : Right thereof

3.7 : Top thereof

3.8 : Perspective view in a open configuration

5.1 : Perspective view in a closed configuration

5.2 : Perspective thereof

5.3 : Front thereof

(Continued)

5.4 : Back thereof
5.5 : Left thereof
5.6 : Right thereof
5.7 : Top thereof
5.8 : Perspective view in a open configuration
7.1 : Perspective view in a closed configuration
7.2 : Perspective thereof
7.3 : Front thereof
7.4 : Back thereof
7.5 : Left thereof
7.6 : Right thereof
7.7 : Top thereof
7.8 : Perspective view in a open configuration
9.1 : Perspective view in a closed configuration
9.2 : Perspective thereof
9.3 : Front thereof
9.4 : Back thereof
9.5 : Left thereof
9.6 : Right thereof
9.7 : Top thereof
9.8 : Perspective view in a open configuration
11.1 : Perspective view in a closed configuration
11.2 : Perspective thereof
11.3 : Front thereof
11.4 : Back thereof
11.5 : Left thereof
11.6 : Right thereof
11.7 : Top thereof
11.8 : Perspective view in a open configuration
13.1 : Perspective view in a closed configuration
13.2 : Perspective thereof
13.3 : Front thereof
13.4 : Back thereof
13.5 : Left thereof
13.6 : Right thereof
13.7 : Top thereof
13.8 : Perspective view in a open configuration
15.1 : Perspective view in a closed configuration
15.2 : Perspective thereof
15.3 : Front thereof
15.4 : Back thereof
15.5 : Left thereof
15.6 : Right thereof

15.7 : Top thereof
15.8 : Perspective view in a open configuration
